UNITED STATES PATENT OFFICE.

JAMES L. HATCHER, OF WINCHESTER, VIRGINIA.

COMBINATION MOUNT FOR MACHINE GUNS.

Application filed December 17, 1928. Serial No. 326,629.

(GRANTED UNDER THE ACT OF MARCH 3, 1883, AS AMENDED APRIL 30, 1928; 370 O. G. 757.)

The invention described herein may be manufactured and used by or for the Government for governmental purposes, without the payment to me of any royalty thereon.

5 The subject of this invention is a combination mount for machine guns.

In employing machine guns at low angles against ground targets, a low mount is required in order to provide stability and 10 afford protection to the gun crew. The assignment of the machine gun as a defense weapon against aerial targets requiring high angle firing necessitates a reconstruction of the standard infantry mount to render it 15 capable of delivering effective fire at the auxiliary targets.

The purpose of the present invention is to reorganize the standard low mount by equipping it with an anti-aircraft adapter.

20 The addition of such an adapter should not alter the characteristics of the standard mount nor should it assume such dimensions or complexity as to unduly increase the weight or interfere with the normal functioning. It should be light, compact and an 25 integral part of the mount or gun, capable of being conveniently moved in adjustment in a minimum time without unduly disturbing the ammunition belt or requiring handling of the hot gun and, further, it must be 30 capable of permitting the efficient direction of fire.

With the foregoing and other objects in view, the invention resides in the novel arrangement and combination of parts and in 35 the details of construction hereinafter described and claimed, it being understood that changes in the precise embodiment of the invention herein disclosed may be made 40 within the scope of what is claimed without departing from the spirit of the invention.

A practical embodiment of the invention is illustrated in the accompanying drawings, wherein:

45 Fig. 1 is a view in side elevation of a mount showing the position of a gun thereon when ordinarily supported for low angle firing;

50 Fig. 2 is a similar view with the gun adapted for anti-aircraft firing;

Figs. 3, 4 and 5 are views respectively in side elevation, plan and longitudinal section of the adapter;

Fig. 6 is a view in front elevation thereof;

Fig. 7 is a view in rear elevation, partly 55 shown in section on the line 7—7 of Fig. 3; and

Fig. 8 is a view in side elevation of the standard gun before receiving the adapter.

The standard machine gun mount for low 60 angle firing consists of a tripod 5 in whose socket is a pintle 6 which carries the cradle 7 by means of a trunnion 8.

The standard gun shown in Fig. 8 is normally mounted on the cradle by means of 65 pins 9 and 10 shown in Fig. 1 and respectively passing through the upper end of the elevating mechanism 11 and the aligned openings 12 in the forward portion of the cradle.

70 The adapter which is to be provided for permitting high angle firing against aerial targets comprises a member 13 placed on the under side of the receiver 14 of the gun. Before putting it into position, however, the 75 rear elevating bracket 15 of the standard gun, shown in Fig. 8, and also the forward spacing members 16 thereon are removed, as the counterparts of these elements are provided on the extremities of the adapter. 80

The apertures which are provided in the receiver for the attaching means of the bracket 15 and spacing members 16 are utilized to receive the rear group of rivets 17 and the forward group 18 whereby the 85 adapter is securely fixed to the gun.

The spaced side plates 19 of the sleigh are each formed with a longitudinally extending slot 20 of sufficient width to receive the rear pin 9 which is inserted through the 90 elevating mechanism 11. The pin 9 is provided adjacent its handle with a collar 21 formed with oblong lugs 22 on its inner side. When the pin is fully inserted to establish the connection, the lugs 22 are receivable in an annular recess 23—23, one being formed in the side plate of the adapter at each end of the slot 20. The diameter of the lugs 22 and recess 23 is greater than the width of the slot so that, when the pin is 95 rotated to the position shown in Figs. 2 and 3 with the lugs 22 disposed perpendicularly with respect to the slot 20, the adapter will be incapable of movement with respect to the elevating mechanism. When the pin is 100 rotated to present the lugs parallel to the slot 20, the adapter may be moved lengthwise of the cradle 7. 105

The gun is in position on the cradle for low angle firing when, as in Fig. 1, it is attached by means of the front and rear pins 9 and 10. The operation necessary to adjust 5 the gun for high angle firing, as indicated in Fig. 2, consists in removing the forward pin 10, rotating the rear pin 9 to permit sliding movement of the gun and then drawing the gun to the rear until the pin 9 is 10 brought up against the forward terminals of the slots 20 in the adapter.

In this position the pin 9 serves as the trunnion of the gun and when turned to locking position it will restrain the gun 15 against forward movement. This procedure is reversed in restoring the gun to its normal mounting for low angle firing.

I claim:

1. A mount for machine guns embodying 20 a support, a cradle trunnioned on the support, an adapter within the cradle, said adapter provided with longitudinal slots and with annular recesses at the terminals of the slots, a pin connecting the forward portion 25 of the adapter of the cradle, a pin in-

serted through the slots of the adapter and 30 through the cradle and an oblong projection on said last named pin engageable in the annular recesses of the adapter.

2. A mount for machine guns embodying 35 a support, a cradle trunnioned on the support, an adapter formed with longitudinal guideways within the cradle, means for attaching the adapter at the front and rear to the cradle, the rear attachment positioned in the guideways of the adapter and cooperating means on the adapter and the rear attachment whereby the adapter is held against sliding movement when the front attachment is not used.

3. A mount for guns embodying a cradle, 45 a gun adapter within the cradle, a sliding connection between the adapter and the rear end of the cradle, means whereby said connection can be adjusted to prevent sliding movement of the connected elements and a removable connection between the cradle and the forward part of the adapter.

JAMES L. HATCHER.
